UNITED STATES PATENT OFFICE.

LEWIS A. HAINES, OF COLUMBUS, OHIO.

BLADING FOR TURBINES.

977,299.

Specification of Letters Patent. Patented Nov. 29, 1910.

Application filed April 25, 1910. Serial No. 557,448.

To all whom it may concern:

Be it known that I, LEWIS A. HAINES, a citizen of the United States, residing at Columbus, in the county of Franklin and 5 State of Ohio, have invented new and useful Improvements in Blading for Turbines, of which the following is a specification.

This invention relates to turbines and more particularly to blading or bucket 10 means for turbines.

One object of the invention is to provide simple and effective means for expeditiously 15 assembling and positively securing turbine blades or buckets to their supporting elements with a resultant increase in the efficiency and commercial advantages of turbine structures generally.

The invention contemplates the association 20 of a plurality of blades or buckets held in spaced relation by separate interposed blocks, the blades or buckets and blocks having a relative configuration and snugly interfitting at their applied portions, and a strand or wire threaded through the blades 25 or buckets to provide a flexible organization which is applied to either a rotating or fixed supporting element.

The invention further consists in the details of construction and arrangement of 30 the several parts which will be more fully hereinafter specified.

For the sake of brevity and also for convenience of description, the term "blade" 35 or "blades," "buckets," or "vanes" wherever used throughout the specification and in the claims will be employed to denote either the rotating blades, buckets or vanes, or the stationary similar devices, and the term "blade carrying element" will denote 40 either the stationary or the rotating blade carrying element or ring.

In the drawings: Figure 1 is an elevation of a blade or bucket carrying element partially in section and embodying the features 45 of the invention. Fig. 2 is an enlarged transverse vertical section through a portion of the structure as shown by Fig. 1. Fig. 3 is a perspective view, partially in full and dotted lines, showing the flexible bar 50 or strip of blades or buckets for application to the carrying element. Fig. 4 is a detail transverse vertical section through a portion of the carrying element and blades or buckets and space blocks showing the latter 55 and the securing means as they appear prior

to the final compressing or swaging operations. Fig. 5 is a top plan view of a portion of the carrying element and blades or buckets and space blocks, and particularly illustrating the formation of the keys on the 60 calking strip and the blocks relatively to the carrying element. Fig. 6 is a detail perspective view of one of the end blades or buckets. Fig. 7 is a detail perspective view of one of the intermediate blades or buckets. Fig. 8 is a detail perspective view of one 65 of the space blocks. Fig. 9 is a detail perspective view of a portion of the calking strip for securing the blades or buckets and space blocks on the carrying element. 70

Each blade carrying element 5 is formed with an outer circumferentially extending channel or groove 6 of greater width than the bases of the blades or buckets and space blocks or spacers disposed therein, and the 75 opposite side walls of each channel or groove are formed with counter-grooves or key seats 7. The blades or buckets 8 are of approximate crescent-shape and are of such length as to have a practical projection outwardly from the blade or bucket carrying element 5 when applied and are held in spaced relation by space blocks or spacers 9 80 formed with front and rear sides of concave and convex contour corresponding to 85 the similar contours of the front and rear sides or faces of the blades or buckets. By this relative contour of the blades or buckets and the blocks or spacers a snug interfitting of the inner or base extremities of the blades 90 or buckets and the blocks or spacers ensues when the said parts are associated in operative relation. The opposite ends of the blocks or spacers 9 are thicker or heavier than the intermediate portions of the same 95 and form practically a straight wall on each side of the series of the blades or buckets and the blocks when the latter parts are assembled. The blocks or spacers 9 are normally of a slightly greater length than the depth 100 of the channel or groove 6, but when the blades or buckets and the blocks or spacers are finally secured in place the top surfaces of the blocks will be flush with the outer surface of the element 5, as will be more 105 fully hereinafter explained.

All of the blades or buckets and the blocks or spacers, except one of the latter, are formed with openings extending there-through between the edge and end portions 110

thereof which are disposed in the channel or groove 6 of the element 5, there being a single opening in each blade or bucket and block or spacer, and the openings of all of 5 the blades or buckets and blocks or spacers are formed in the same position or have an exact location so that when the blades or buckets and the blocks or spacers are assembled the openings therethrough will pro- 10 vide a practically continuous bore. Through the medium of the openings in the blades or buckets and blocks or spacers and respectively designated by the numerals 10 and 11, the said parts may be assembled to form a 15 flexible bucket bar, as it were, through the medium of a strand or wire 12 which is threaded through the openings. It is preferred, in order to tightly associate and cause a preliminary snug interfitting of the blades 20 or buckets and the blocks or spacers, that the latter be strung on the strand or wire 12 in successive groups of predetermined number and tightened up by suitable clamping means, one group first being clamped, a sec- 25 ond group then being forced up against the first group and clamped, and the succeeding groups likewise applied until the requisite number of blades or buckets and blocks or spacers has been strung on the wire. The 30 wire ends will project from the end blade or bucket or block or spacer at each extremity of the flexible bar so produced and all of the buckets and blocks will be held tightly clamped on the wire and in this condition 35 disposed in the channel or groove 6, the bar or strip of buckets and blocks being gradually bent to conform to the curvature of the base of the said channel or groove 6 and the buckets thereby caused to assume a proper 40 radial relation to the carrying element 5. After the flexible bar of buckets and blocks has been fully applied around the carrying element 5, the projecting ends of the strand or wire 12 are bent downwardly and passed 45 through to the inner side of the element 5, as at 13, and secured by bending the same, but prior to the final securing of the strand or wire ends a suitable clamping band or other clamping means to exert a 50 drawing action on the blades or buckets is applied over the latter and operated to gradually draw and tighten the series of buckets and blocks toward the two ends where the ends of the wire are to be secured, 55 and when the proper degree of tightness has been obtained the wire ends are then bent in opposite directions against the inner side or periphery of the carrying element 5 as shown. 60 After the wire ends have been secured as just explained, a key block, as 14, is inserted between the terminal blades or buckets adjacent to the bent ends of the wire, said key block being of the same contour as the re- 65 maining blocks 9 but without the opening

11 therethrough. To accommodate a close bending of the wire ends against the base portions of the end buckets of the series, said buckets have depending grooves as at 15, one in each bucket, and into these 70 grooves the wire sinks or is drawn when the final tightening of the flexibly associated series of blades or buckets and blocks is effected.

As hereinbefore intimated, the channel or 75 groove 6 is wider than the blades or buckets and blocks, and in the space formed between the one side of the associated blades or buckets and blocks and adjacent side wall of the channel a copper calking or calking strip 16 is introduced and hammered or expanded so as to force a portion thereof into the adjacent groove 7 to provide a key, as at 17. This copper or analogous calking or calking strip 16 may be compressed into the space as just 80 specified through the medium of a suitable pneumatic hammer, and primarily the said calking or calking strip will snugly fit the space in cross-section and also slightly project above and outwardly beyond the outer 85 edge portion of the element 5. When the copper calking or calking strip 16 is secured in place, the outer edge thereof will be flush with the outer edge portion of the element 5. The upper portions of the blocks or spacers 90 9 are next subjected to a swaging action by introducing a pneumatic hammer between the buckets 8 and against the said blocks and the upper slightly projected portions of said blocks, or the metal embodied in said projecting portions will be compressed into the body of the blocks and cause the latter to expand and entirely close up any cracks or 100 crevices between the inner extremities of the blades or buckets and the blocks and also 105 cause the latter to expand laterally into the groove 7 opposite that engaged by the expanded portion or key 17 of the copper calking or calking strip 16 to form key means 110 18. When this compression of the blocks will have been completed their upper portions will also be flush with the outer edge 115 portions of the carrying element 5 and copper calking or calking strip 16, and the buckets and blocks will be securely and positively held in the carrying element and resist any tendency to loosening or displacement. The buckets and blocks may be replaced at any time found necessary by first cutting out the copper calking or calking strip 16 and then subsequently inserting a new calking strip in the manner hereinbefore explained.

What is claimed is:

1. In a turbine, the combination with a 125 circumferentially channeled supporting element, of a flexible blade bar composed of a plurality of blades and space blocks alternately arranged and threaded on a stringer, the bar being applied in the channeled sup- 130

porting element and having the ends of the stringer passed through and secured to said supporting element.

2. In a turbine, the combination with a supporting element having a circumferential channel, of a plurality of alternately arranged blades or buckets and space devices of relative configurations, the blades or buckets and space devices being preliminarily disposed on a flexible stringer and applied in and bent around the said channel, the stringer having its extremities inserted through and secured to the supporting element.
3. In a turbine, the combination with a supporting element, of a flexible blade or bucket bar applied around and secured to said supporting element and having a stringer extending therethrough, the blade or bucket bar being prepared preliminarily to its application to the supporting element and secured to the latter, and a key device inserted between the contiguous ends of the applied bar and fitted over the extremities of the stringer.
4. In a turbine, the combination with a supporting element, of a flexible blade or bucket bar applied around and secured to said supporting element and having a stringer extending therethrough, a key device inserted between the ends of the flexible blade or bucket bar when the latter is applied, and calking means interposed between the applied blade or bucket bar and a portion of the supporting element and having a part of the same projected into the said element.

5. In a turbine, the combination with a supporting element, of a flexible blade or bucket bar applied around and secured to said supporting element, the blade or bucket

bar being composed of a plurality of blades or buckets and space devices and a flexible strand threaded through the blades or buckets and space devices prior to the application of the latter to the supporting element, the extremities of the flexible strand being inserted through portions of the supporting element and serving as a holding means for the blade or bucket bar.

6. In a turbine, the combination with a supporting element having a groove therein, of a flexible motive agent engaging means provided with a stringer extending therethrough, the extremities of the stringer being removably inserted through a portion of the supporting element, and calking means interposed between a portion of the supporting element and the motive agent engaging means.

7. In a turbine, the combination with a supporting element having a groove therein, of a flexible blade or bucket bar having a stringer extending therethrough and preliminarily prepared and applied to the groove of the supporting element, the blade or bucket bar being composed of a plurality of alternately arranged blades or buckets and space devices closely interfitting and disposed in relative position prior to application to the supporting element, a wedge device interposed between the contiguous ends of the applied bar, and calking means interposed between one side of the bar and the adjacent portion of the supporting element.

In testimony whereof I have hereunto set my hand in presence of two subscribing witnesses.

LEWIS A. HAINES.
